[57] CLAIM

The ornamental design for an ice cream confection, as shown and described.

DESCRIPTION

FIG. 1 is a top right isometric perspective view of an ice cream confection showing my new design.

FIG. 2 is a left side elevational view of the design.

FIG. 3 is a right side elevational view of the design.

FIG. 4 is a bottom plan view of the design.

FIG. 5 is a left end, elevational view, the right end being a mirror image thereof; and,

FIG. 6 is an enlarged partial, elevational sectional view taken along line 6—6 of FIG. 1.
